(57) **CLAIM**

The ornamental design for a hydrant monitoring cap, as shown and described.

DESCRIPTION

FIG. 1 is an elevated front perspective view of a hydrant monitoring cap in accordance with the present design.

FIG. 2 is a lower front perspective view for the hydrant monitoring cap of the present design.

FIG. 3 is a side view for the hydrant monitoring cap of the present design.

FIG. 4 is a top view for the hydrant monitoring cap of the present design.

FIG. 5 is a bottom view for the hydrant monitoring cap of the present design.

FIG. 6 is an elevated front perspective view for the hydrant monitoring cap of the present design, with the hydrant monitoring cap installed to a hydrant.

FIG. 7 is a side view for the hydrant monitoring cap of the present design, with the hydrant monitoring cap installed to a hydrant.

FIG. 8 is an elevated front perspective view for the hydrant monitoring cap of the present design, with the hydrant monitoring cap installed to a hydrant; and,

FIG. 9 is a side view for the hydrant monitoring cap of the present design, with the hydrant monitoring cap installed to a hydrant.
